UNITED STATES PATENT OFFICE

99,389

DESIGN FOR A TEXTILE FABRIC

Marcel Christen, New York, N. Y., assignor to
Levin-Forman Silk Corporation, New York,
N. Y., a corporation of New York

Application March 7, 1936, Serial No. 61,517

Term of patent 3½ years

To all whom it may concern:

Be it known that I, Marcel Christen, a citizen of the United States and a resident of the city and State of New York, with a post office address at No. 202 West 40th Street, in the Borough of Manhattan, city and State of New York, have invented a new, original, and ornamental Design for a Textile Fabric, of which the following is a specification, reference being had to the accompanying drawing, forming part thereof:

In which: the figure of the drawing represents a plan view of a textile fabric incorporating my ornamental design, the same being sectioned for color.

The criss-cross lanes are white, the alternate intersections of the criss-cross lanes being of solid dark tone, and the area along the length of each lane adjacent such intersections has a gradual

decrease in concentration from solid to particle formation of the same tone.

The square formations defined by the criss-cross lanes have a background of a solid tone lighter and different from the first mentioned dark tone. In such background and at opposite corners distant from the dark toned lane intersections are substantially square areas colored with the first named dark tone and surrounding and between such dark toned areas in the background are paths of the same dark tone but gradually decreasing in concentration from solid to particle formation.

I claim:

The ornamental design for a textile fabric, as shown, and described.

MARCEL CHRISTEN.
